FEEDING AND PRESSER MECHANISMS FOR
SEWING MACHINESFrederick F. Zeier, Stratfield, Conn., assignor to
The Singer Manufacturing Company, Elizabeth,
N. J., a corporation of New Jersey

Application April 2, 1946, Serial No. 658,963

23 Claims. (Cl. 112—212)

1

This invention relates to sewing machines and, more particularly, to that class of sewing machine which utilizes a clamp-feed mechanism in conjunction with a presser-foot of the type which is continuously in engagement with the work during the sewing operation.

It is an object of this invention to provide, in a machine of this type, improved means for lifting simultaneously the upper feeding foot and the presser-foot off the work with a minimum of force.

Another object of this invention is to provide, in the present class machine, improved feeding and presser-foot lifting mechanism which will enable operation of the machine at a much higher rate of speed than heretofore was possible.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Fig. 1 represents a rear side elevation of a sewing machine in which the present invention is incorporated.

Fig. 2 represents a top plan view of the present machine.

Fig. 3 represents a left end elevation of the sewing machine, showing the stitching and feeding mechanisms with the bed and work-supporting plate in section, and with the needle in its uppermost position.

Fig. 4 represents a left side elevation of the stitching and feeding mechanisms as removed from the sewing machine frame and with the needle in its lowermost position.

Fig. 5 represents a sectional view of the upper feeding and stitching mechanism, taken substantially along line 5—5 of Fig. 1.

Fig. 6 represents a sectional view of a portion of the feed-bar actuating mechanism, taken substantially along line 6—6 of Fig. 3.

Fig. 7 represents a sectional view showing a presser-bar lifting means and taken substantially along line 7—7 of Fig. 5.

Fig. 8 represents a sectional view showing a portion of the presser-bar with its associated elements and taken substantially along line 8—8 of Fig. 5.

Fig. 9 represents a front elevation of the springs shown in Fig. 1.

Fig. 10 represents a sectional view showing the

presser-lifting mechanism in its normal position and taken substantially along line 10—10 of Fig. 2.

Fig. 11 is an illustration in side elevation of the 5 presser-lifting mechanism at that point in its cycle at which the presser springs are fully untensioned.

Fig. 12 is an illustration of the presser-lifting mechanism at that point in the cycle at which 10 the presser-bar and top feed-bar are fully raised off the work.

Referring to the drawings, the invention is embodied in a sewing machine having a frame comprising a bed 16 from one end of which rises a standard 17 of an overhanging bracket-arm 18 terminating in a head 19. Journaled for rotation within this frame is a main- or arm-shaft 20 carrying at its outer end the usual belt-driven balance-wheel 21 and at its inner end a counterbalanced needle-bar actuating crank 22. The shaft 20 is connected by a clip-belt 23, herein shown incompletely, to a belt-pulley 24 fast upon the outer end of a lower main- or bed-shaft 25 journaled for rotation in the bed 16, the ratio between the shafts 20 and 25 being one-to-one.

Actuated by the bed-shaft 25 is the usual lower four-motion work-feeding mechanism, including a feed-dog 26, and the looper mechanism including a chain-stitch looper 27. For the sake of brevity, a detailed description of the four-motion feeding mechanism will not be given herein, inasmuch as the same is fully described and claimed in my U. S. Patent No. 2,292,258, August 4, 1942.

35 With regard to the looper mechanism disclosed in the drawings, it will suffice to say that the looper 27 is preferably of the two motion type having loop-seizing and -shedding movements only in the line of feed, the looper advancing to seize the needle-loop in a direction opposed to the direction of feed.

Referring now to the mechanism within the machine-head 19, it will be seen in Figs. 1, 3 and 4 that a needle-bar actuating link 28 is pivotally mounted upon the crank 22 by means of a screw 29. The lower end of the link 28 is apertured to receive a pin 30 integral with a split collar 31 clamped upon the usual needle-bar 32. Carried by the lower end of the needle-bar 32 is a suitable needle 33. Through the mechanism just described the needle-bar 32 is reciprocated endwise in proper timed relation with the complementary looper 27 to produce chain-stitches.

The needle-bar 32 is journaled in bearing members 34 and 35 projecting from the needle-bar

55

frame 36 which is provided with a horizontally projecting fulcrum-rod 37 journaled within the lug 38 of the machine head 19.

The needle-bar frame 36, in the machine illustrated, is oscillated in timed relation with the four-motion feed-dog 26 through mechanism comprising a rock-lever 39 (see Fig. 1) preferably clamped at its lower end 40 upon the end portion of the fulcrum-rod 37. At its upper end, the rock-lever 39 is pivotally connected, by means of a bolt 41 and nut 42, to one end of a relatively short pitman 43 formed at its other end with a strap 44 embracing an adjustable eccentric 45 secured to rotate with the arm-shaft 20. It will be understood that as the arm-shaft 20 is rotated, the eccentric 45 actuates the pitman 43 which in turn operates the rock-lever 39 to oscillate the needle-bar frame 36 about the axis of the fulcrum-rod 37. The amplitude of oscillatory movement imparted to the needle-bar frame is dependent upon the amount of eccentricity of the eccentric 45 and, in order to vary the amplitude of oscillatory movements of the needle-bar frame to harmonize with the stitch-length to which the lower feeding mechanism is set, the eccentric is made adjustable. A complete description of this type of adjustable eccentric may be found in the U. S. patent of W. Myers, No. 2,128,031, August 23, 1938. For a more detailed description of the present type of needle-bar mechanism, reference may be had to my U. S. Patent No. 2,329,681, September 14, 1943.

Referring particularly to Figs. 3 and 4, the needle-bar frame 36 has a vertically apertured bearing lug 46 formed thereon rearwardly of the bearing portion 35. Slidably mounted within this bearing lug 46 is a top feed-bar 47 carrying at its lower end a feeding foot 48 which is adapted to cooperate with the needle 33 and the lower feed-dog 26 in the feeding of the work over the bed-plate 49. Since the feed-bar 47 is carried by the needle-bar frame 36, the latter element will impart the same amplitude of vibrating motion in the line of feed to both the needle-bar 32 and the top feed-bar 47.

The upper end of the top feed-bar 47 is provided with a cross-pin 50 which is slidably disposed within the forked free end 51 of a substantially horizontally disposed feed-lift lever or arm 52. The confined end of the lever 52 is pivotally mounted upon a fulcrum-pin 53 which is secured within the lower rear portion of the machine head 19.

In order to prevent the feed-bar 47 from turning about its longitudinal axis, the top portion thereof is provided with a pair of cheeks 54 which carry the cross-pin 50 and which embrace the forked portion 51 of the bar 52.

Pivotedly carried by and at the center of percussion of the feed-lift lever 52 is a pivot-pin 55 of a bell-crank lever having arms 56 and 57 of which the arm 56 is pivotally connected by a pin 58 to the lower end of a link 59. The upper end portion of the link 59 is connected by means of a pin 60 to an actuating crank 61 carried by one end of a rock-shaft 62 which is journaled in bearing lugs 63 and 64 provided on the machine bracket-arm 18 and head 19, respectively. The rock-shaft 62 is disposed in parallelism with the needle-bar actuating shaft 20.

Secured upon the opposite end portion of the rock-shaft 62, by means of screws 65, is a short crank 66 carrying a pin 67 which is pivotally embraced by the forked end of a pitman 68 whose other end terminates in an eccentric strap 69.

The strap 69 embraces an adjustable eccentric 70 secured to rotate with the arm-shaft 20. It will be understood that as the arm-shaft 20 is rotated, the eccentric 70 actuates the pitman 68 which, in turn, imparts rocking movements to the rock-shaft 62 through the medium of the crank 66. The amplitude of these movements may be varied by adjusting the throw of the adjustable eccentric 70. For a more detailed description of an adjustable eccentric of this type, reference may be had to the U. S. patent of A. H. DeVoe, No. 14,218, reissued November 28, 1916.

Pressing downwardly upon the feed-lift lever 52, at a point between the bell-crank pivot point 55 and the forked end 51 thereof, is one end of a spring-biased blade-lever 71 which is located outside of and rearwardly adjacent to the machine bracket-arm 18. The other end of this lever 71 is biased upwardly by means of a coil spring 72 which is operatively connected to an arm 73 pivotally mounted upon the bracket-arm 18. The lower end of the spring 72 is pivotally connected to the lever 71 by means of a bolt 74 and a nut 75. As illustrated more particularly in Figs. 5, 7 and 10, the lever 71 is fulcrumed adjacent to the feed-lift crank 52 upon a knife-edge 76 of a fulcrum-piece 77 extending from a stub-shaft 78 which is rockably mounted within an aperture 79 formed in the lower portion of the machine head 19. In order to prevent the spring-biased lever 71 from exerting any side thrust upon the feed-lift lever 52, a steel ball 80 is held, by means of a sheet metal cage 81, between said lever 71 and crank 52. The cage is secured to the crank 52 by means of screws 83.

Referring particularly to Figs. 5 and 7, the lever 71 is apertured so as to afford clearance for a guide-pin 84 projecting upwardly from the shelf portion 85 of the head 19 and extending through the forked end of a guide-arm 86 which is clamped by means of a screw 87 to the upper reduced portion of a presser-bar 88 which will be described hereinbelow. The pin 84 thus prevents the lever 71 from moving sidewise.

The oscillatory motion of the above noted rock-shaft 62 causes the bell-crank lever 56, 57, to swing in a vertical plane about its pivot-pin 55 in the feed-lift lever 52, so that the arm 57 thereof successively tends to raise and lower. Referring to Fig. 7, the arm 57, on its downstroke, engages the shelf 85, and further movement of the bell-crank lever can only result in raising the pivot point thereof, which latter action will, of course, raise the forked end 51 of the feed-lift lever 52 with the consequence that the top feeding-foot 48 is lifted clear of the throat-plate 49, as is illustrated in Fig. 3. When the arm 56 moves downwardly, thus to throw the arm 57 upwardly relatively thereto, the spring-biased lever 71 forces the member 52 downwardly and the foot 48 is forced against the work and the arm 57 lifts off the shelf 85. Continuous oscillation of the rock-shaft 62 will, therefore, cause the top feed-bar 47 alternately to rise and fall under the continual pressure of the spring-biased lever 71. The motions of the rock-shaft 62 are synchronized with those of the needle-bar 32 so that the usual compound feeding mechanism will be effected.

Adjustment of the rock-shaft actuating eccentric 70 will effect adjustment in the amplitude of the vertical movements imparted to the top feed-bar.

The machine head 19 is provided with a vertically disposed stationary bearing member 89 in which the above mentioned presser-bar 88 is slid-

ingly mounted so as to be located slightly rearwardly of the top feed-bar 47 and out of the line of feed at that side of the line of feed nearest to the machine bracket-arm 18. A usual type of presser-foot 90 is carried by the lower end of this presser-bar 88. Formed in the upper portion and between the ends of the presser-bar 88 is a slot 91, adapted to receive the free end of a secondary spring-biased blade-lever 92 which presses downwardly against the presser-bar. This lever 92 is located substantially beneath the primary lever 71 and the other end thereof is biased upwardly by means of a secondary coil spring 93 which is operatively connected to a bracket 94 carried by the bracket-arm 18. The lower end of the spring 93 is pivotally connected to the lever 92 by means of an eye 95. As illustrated more particularly in Figs. 5, 7 and 10, the lever 92 is fulcrumed adjacent to the lever 71 upon the knife-edge 76.

By means of the secondary coil spring 93, the presser-foot 90 is constantly urged downwardly against the work and thus cooperates with the above described feeding mechanism in the feeding of the work.

As hereinabove noted, one end of the lever 71 is pivotally secured to the coil spring 72 by means of the bolt 74. Referring more specifically to Figs. 1, 2 and 10, the lower end of the spring 72 is secured to the lower cup-shaped member 96 which is telescopically fitted within the upper and reversely directed cup-shaped member 97 whose upper portion has a threaded rod 98 projecting upwardly therefrom. Clamped upon the rod 98 is a split collar 99 (see Fig. 2) having a threaded bolt portion 100 extending laterally therefrom. Pivotally embracing the bolt 100 is the arm 73 held upon the bolt by means of nuts 101. The upper end of the spring is suitably secured to the member 97, thus to bias the lever 71 upwardly. The two cup-shaped members 96 and 97 form a substantially airtight unit whose purpose is to dampen the violent spring vibrations which would otherwise occur when the spring 72 passes through its critical phases.

The applied pressure of the spring 72 may be varied by shifting the rod 98 relative to the clamp collar 99, when loosened by means of a stop-nut 102 which is carried by the threaded upper portion of the rod 98. A clamp screw 103 is used for tightening the collar 99 about the rod 98 in the set position of the collar.

Pivotally carried by the bolt 100 is the bracket 94 having an inverted U-shaped portion comprising the apertured downturned side pieces 104 and 105 which embrace the apertured end portion of the arm 73. The nuts 101 and a washer 106 retain the bracket 94 in place on the arm 73.

The short horizontally disposed portion of the bracket 94 has mounted thereon, by means of nuts 107, a rod 108 the lower end of which has secured thereto the secondary coil spring 93. The lower portion of this spring is formed as a hook 109 which is connected to the rear end of the lever 92 by means of the eye 95. The depending portion or limb of the bracket 94 has pivotally connected to its lower end, by means of a rivet 110, a steady-link 111 which has its other end pivotally connected to the rear end of lever 92 by means of a rivet 112.

Referring particularly to Figs. 2 and 10, the fulcrum line 76 of the spring-biased levers 71 and 92 is so located that the levers are each of the first class; the portion of each lever extending forwardly of the fulcrum line 76 being very much shorter in length than that portion which ex-

tends from each of the respective lever pivot points at 74 and 112 to the fulcrum line at 76. By means of these levers or multiplying means 71 and 92, the amplitude of vertical movements of both the feed-bar 47 and the presser-bar 88, is, in each instance, multiplied by at least five times, thus to impart to each bar a force five times greater than the respective coil springs would impart thereto if they were acting directly upon a respective lever. Thus, a relatively light spring is adequate in each case for supplying the proper pressure to the presser-foot and feed-foot. Tests have proven that by using such a multiplier, superior results have been attained as compared to the results attained when using the same top feeding and presser elements but with springs each having about five times the stiffness of the respective springs 72 and 93 and applied to bear directly upon the lever 52 and the bar 88. Apparently there is much advantage to be gained by using a light weight spring coupled with a "multiplier" as compared to using a heavier weight spring which is applied directly upon the lever 52 or upon the bar 88. These tests have shown that the use of the present multiplier mechanisms completely obviates the tendency of the feet 48 and 90 to flutter when the machine is operating at a high rate of speed. It is an advantage to use a spring having a high natural frequency for this purpose.

For a more complete explanation of this "multiplier" action, reference may be had to my U. S. Patent No. 2,428,762, granted October 7, 1947, and entitled "Sewing machine."

The present machine is also provided with manually operable presser- and top feed-bar lifting means designed to keep at a minimum the lifting force required. Broadly, these means comprise elements adapted, under treadle-controlled action, to remove completely the tension of each coil spring from the respective levers and to swing the knife-edge fulcrum member 77 away from the levers 71 and 92 to permit the presser- and feed-bars freely to be raised off the work.

In general, the present lifting mechanism comprises a self-contained frame-work 113 carried by the machine bracket-arm 17. Within this frame-work 113 are mounted two sets of Geneva stops 114 and 115 geared together in order to provide a series of successive motions all produced by a single downward movement of the usual foot-actuated treadle which is connected to the Geneva stops by means of a chain 116 and a pivoted arm 117, which latter carries a segment-gear 118. Responsive to an initial movement of the treadle-chain 116, through the connecting means of the segment-gear 118 and a pinion 119 engaged thereby, the primary Geneva stop 114 raises an arm 120 which actuates a toggle-joint comprising arms 121 and 122 pivotally connected as at 123. Arms 121 are pivotally carried by the frame-work 113 as at 124, and the other arms 122 of the toggle-joint are pivotally connected as at 125 to an arm 126 which in turn is carried pivotally by the frame-work as at 127. The hereinabove noted arm 73 is integral with arm 126 and therewith forms a bell-crank lever which, under the action of the toggle-joint, swings about its pivot 127 for the purpose of moving the coil springs 72 and 93 into untensioned positions.

At this point in the cycle, the spring pressures are entirely removed from the presser-bar and top feed-bar as may be seen from Fig. 11. Further downward movement of the treadle chain

116 will not move the bell-crank 126, 13, and the coil springs 72 and 93 due to the inherent lost-motion action of the Geneva stop 114, but the second Geneva stop 115 then becomes effective to actuate segment gear 128 which in turn imparts a forward linear motion to a horizontally disposed rack-bar 129 slidably mounted within the frame-work 113 and within a bearing aperture 130 formed in the head 19.

The forward end portion of this rack 129 engages gear teeth 131 provided on the end portion of the above noted stub-shaft 78 which carries the knife-edge 76 and, therefore, the linear movement imparted to the rack is effective to rotate the stub-shaft, thereby to remove the fulcrum point from the spring-biased levers 71 and 92 for the purpose of providing proper clearance between each of the levers 71 and 92 and the fulcrum so the presser-bar and top feed-bar may be raised freely.

Threaded into the fulcrum-piece 77 of the stub-shaft 78, at a point eccentric to the axis of rotation thereof, is a screw 132 (see Fig. 7) of which an exposed shoulder portion 133 enters a slot 134 provided adjacent one end portion of a sheet metal arm 135, the other end of which arm is secured pivotally to the under body of the machine bracket-arm 18 by means of a screw 136. The free end of the arm 135, adjacent the slotted portion thereof is bent to form a lip 137 and underlies the guide-arm 86 carried by the presser-bar 88. The turning motion of the stub-shaft, therefore, throws the screw 132 in an arcuate path, thereby raising the free end portion of the sheet metal arm 135 which in turn lifts the presser-bar 88. This upward movement of the presser-bar lifts the top feed-bar 47 through the medium of finger piece 138 carried by the guide-arm 86 and underlying, at its lower end, the feed-lift lever 52. A screw 139 secures the finger piece 138 within an aperture 140 provided in the guide-arm 86. Fig. 12 illustrates this final step in the cycle.

Upon releasing the manually applied force exerted on the treadle-chain 116, the above described mechanism will return to its normal position under the force of a pair of tension springs 141 which are effective to retension the coil springs 72 and 93, as the springs 141 operate through the medium of the toggle joint, 121, 122.

For a more complete description of the present type of Geneva stop device, reference may be had to my U. S. Patent No. 2,430,440, granted November 4, 1947, and entitled "Presser-bar mechanism for sewing machines."

From the above description it is to be understood that the levers 71 and 92 each functions to impose upon the respective springs 72 and 93 a range of movement materially greater than that of either the feed-bar 47 or presser-bar 88 respectively. From this it will be understood that for every upward movement made by either the feed- or presser-bar, there is applied respectively thereto a quantum of spring-applied force which is greatly in excess of that which would be applied thereto if the springs 72 and 93 were each connected directly to the respective bars 47 and 88. Thus it is possible to use a pair of relatively lightweight springs and still have available the requisite amount of spring pressure for efficiently biasing the work-engaging elements toward the work.

Furthermore, the present device, although fitted with means for applying heavy spring forces upon the feed- and presser-bar, is also equipped with means whereby the springs may be

relaxed preparatory to lifting said bars simultaneously.

Having thus set forth the nature of the invention, what I claim herein is:

5. In a sewing machine, a frame including a bracket-arm, a feed-lift arm pivotally carried upon said bracket-arm, a four-motion upper feed-foot, means to connect said foot to said arm, a lever pivotally mounted upon said feed-lift arm, means to impart a vibratory motion to said lever, means reacting upon said bracket-arm to arrest the motion of said lever in one direction thereby to impart a feed-lift motion to said foot, and means for imparting feed-advance and -return motions to said foot.
10. In a sewing machine, a frame including a bracket-arm, a feed-lift arm pivotally carried upon said bracket-arm, a four-motion upper feed-foot for advancing work through said machine, means to connect said foot with said arm, spring means for biasing said foot toward the work, a lever pivotally mounted upon said feed-lift arm, means to impart a vibratory motion to said lever, means reacting upon said bracket-arm to arrest the motion of said lever in one direction thereby to impart a feed-lift motion to said foot in opposition to said spring means, and means for imparting feed-advance and -return motions to said foot.
15. In a sewing machine, a frame including a bracket-arm, a feed-lift arm pivotally carried upon said bracket-arm, a four-motion upper feed-foot for advancing work through said machine, means to connect said foot with said arm, a presser-foot slidably mounted within said bracket-arm, a pair of springs, each spring being adapted for pressing one of said feet toward the work, a lever pivotally mounted upon said feed-lift arm, means to impart a vibratory motion to said lever, means reacting upon said bracket-arm to arrest the motion of said lever in one direction thereby to impart a feed-lift motion to said foot in opposition to one of said springs, means for imparting feed-advance and -return motions to said feed-foot, and a single manually operable means for lifting both of said feet off the work.
20. In a sewing machine, a frame including a bracket-arm, a feed-lift arm pivotally carried upon said bracket-arm, a four-motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
25. In a sewing machine, a frame including a bracket-arm, a feed-lift arm pivotally carried upon said bracket-arm, a four motion upper feed-foot for advancing work through said machine, means to connect said foot with said arm, a spring for pressing said feed-foot toward said work, means comprising a lever of the first order interposed between said spring and said feed-foot for imposing upon said spring a range of movement materially longer than that of said feed-foot, a lever pivotally mounted upon said feed-lift arm, actuating means for imparting a
30. In a sewing machine, a frame including a bracket-arm, a feed-lift arm pivotally carried upon said bracket-arm, a four-motion upper feed-foot for advancing work through said machine, means to connect said foot with said arm, a presser-foot slidably mounted within said bracket-arm, a pair of springs, each spring being adapted for pressing one of said feet toward the work, a lever pivotally mounted upon said feed-lift arm, means to impart a vibratory motion to said lever, means reacting upon said bracket-arm to arrest the motion of said lever in one direction thereby to impart a feed-lift motion to said foot in opposition to said spring means, and means for imparting feed-advance and -return motions to said foot.
35. In a sewing machine, a frame including a bracket-arm, a feed-lift arm pivotally carried upon said bracket-arm, a four-motion upper feed-foot for advancing work through said machine, means to connect said foot with said arm, a presser-foot slidably mounted within said bracket-arm, a pair of springs, each spring being adapted for pressing one of said feet toward the work, a lever pivotally mounted upon said feed-lift arm, means to impart a vibratory motion to said lever, means reacting upon said bracket-arm to arrest the motion of said lever in one direction thereby to impart a feed-lift motion to said foot in opposition to said spring means, and means for imparting feed-advance and -return motions to said foot.
40. In a sewing machine, a frame including a bracket-arm, a feed-lift arm pivotally carried upon said bracket-arm, a four-motion upper feed-foot for advancing work through said machine, means to connect said foot with said arm, a presser-foot slidably mounted within said bracket-arm, a pair of springs, each spring being adapted for pressing one of said feet toward the work, a lever pivotally mounted upon said feed-lift arm, means to impart a vibratory motion to said lever, means reacting upon said bracket-arm to arrest the motion of said lever in one direction thereby to impart a feed-lift motion to said foot in opposition to one of said springs, means for imparting feed-advance and -return motions to said feed-foot, and a single manually operable means for lifting both of said feet off the work.
45. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
50. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
55. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
60. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
65. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
70. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.
75. In a sewing machine, a frame including a bracket-arm, a feed-lift arm pivotally carried upon said bracket-arm, a four motion upper feed-foot for advancing work through said machine, means to connect said foot with said arm, a yoke pivotally carried by said frame, a needle-bar slidably mounted within said yoke, a bearing member carried rigidly with said yoke, a four-motion feed-bar slidably mounted within said bearing member, means for rocking said yoke, a feed-lift arm pivotally carried upon said bracket-arm, means to connect said feed-bar with said arm, spring means for biasing said foot toward the work, a lever pivotally mounted upon said feed-lift arm, means to impart a vibratory motion to said lever, and means reacting upon said bracket-arm to arrest the motion of said lever in one direction thereby to impart a feed-lift motion to said feed-bar in opposition to said spring means.

vibratory motion to said latter lever, means adapted to arrest the motion of said latter lever in one direction so that continued operation of said actuating means in one direction will impart a feed-lift motion to said foot in opposition to said spring, and means for imparting feed-advance and -return motions to said foot.

6. In a sewing machine, a frame including a bracket-arm, a feed-lift arm pivotally carried upon said bracket-arm, a four-motion upper feed-foot for advancing work through said machine, means to connect said foot with said arm, a lever having one end thereof operatively associated with said arm, a spring connected to the other end of said lever so as to force said foot against the work, a fulcrum member cooperatively associated with said lever and in engagement therewith at a point adjacent the arm for multiplying the applied force of said spring and for applying the resultant upon said foot, a bell-crank lever pivotally mounted upon said feed-lift arm, means to impart a vibratory motion to one limb of said bell-crank lever, means reacting upon said bracket-arm to arrest the motion of the other limb of said bell-crank lever in one direction thereby to impart a feed-lift motion to said foot in opposition to said spring, and means for imparting feed-advance and -return motions to said foot.

7. In a sewing machine, a frame including a bracket arm, a yoke pivotally carried by said bracket-arm, a needle-bar slidably mounted within said yoke, a bearing member carried rigidly with said yoke, a four-motion feed-bar slidably mounted within said bearing member for feeding work through said machine, means for rocking said yoke, a feed-lift arm pivotally carried at its one end upon said bracket-arm, means to connect said feed-bar with the other end of said arm, a spring for pressing said feed-bar toward the work, means comprising a lever of the first order interposed between said spring and said feed-bar for imposing upon said spring a range of movement materially longer than that of said feed-bar, a bell-crank lever pivotally mounted upon said feed-lift arm, means to impart a vibratory motion to one limb of said bell-crank lever, and means reacting upon said bracket-arm to arrest the motion of the other limb of said bell-crank lever in one direction thereby to impart a feed-lift motion to said feed-bar in opposition to said spring.

8. In a sewing machine, the combination of a plurality of work-engaging feet, a plurality of springs, each spring being adapted for pressing a respective one of said feet toward the work, means interposed in operative relation between each of said springs and its associated foot thereby to impose upon each spring a range of movement materially longer than that of its respective associated foot, and intermittently effective lifting means for one of said feet, said lifting means being adapted to lift said foot against the force of its associated spring.

9. The combination in a sewing machine having a frame including a work-support, a presser-foot carrying bar, a feeding-foot carrying bar, means for endwise reciprocating and laterally jogging said feeding foot carrying bar, a pair of springs, each spring being adapted for pressing a respective one of said carrying bars toward the work, means interposed between each of said springs and its associated carrying bar for multiplying the applied force of each spring and applying the resultant upon a respective one of said

carrying bars, and a single manually operable means for lifting both carrying bars away from the work.

10. In a sewing machine, the combination of a plurality of work-engaging feet, a plurality of springs, each spring being adapted for pressing a respective one of said feet upon the work, means comprising a lever of the first order interposed between each of said springs and its associated foot for imposing upon each spring a range of movement materially longer than that of its associated foot, and a single manually operable means for lifting all of said feet away from the work.

15. In a sewing machine, the combination of a plurality of work-engaging feet, a plurality of coil-springs, each coil-spring being adapted for pressing a respective one of said feet upon the work, a plurality of relatively stiff levers of the first order, each lever having one end thereof operatively connected to a respective one of said feet and the other end thereof operatively connected to a respective one of said coil-springs, each lever being adapted to impose upon its associated coil-spring a range of movement materially longer than that of its associated foot, intermittently effective lifting means for one of said feet, said lifting means being adapted to lift its associated foot against the force of its associated coil-spring, and a single manually operable means for lifting all of said feet away from the work.

20. 11. In a sewing machine, the combination of a plurality of work-engaging feet, a plurality of coil-springs, each coil-spring being adapted for pressing a respective one of said feet upon the work, a plurality of relatively stiff levers of the first order, each lever having one end thereof operatively connected to a respective one of said feet and the other end thereof operatively connected to a respective one of said coil-springs, each lever being adapted to impose upon its associated coil-spring a range of movement materially longer than that of its associated foot, intermittently effective lifting means for one of said feet, said lifting means being adapted to lift its associated foot against the force of its associated coil-spring, and a single manually operable means for lifting all of said feet away from the work.

25. 12. The combination in a sewing machine having a frame including a work-support, a reciprocating presser-foot carrying bar, a feeding-foot carrying bar mounted for endwise reciprocating and laterally jogging work-feeding movements, a pair of springs, each spring being adapted for biasing a respective one of said bars toward said work-support, means comprising a motion-multiplying member interposed between each of said springs and its associated bar for imposing upon each spring a range of movement materially longer than that of its associated bar, intermittently effective lifting means for lifting said feeding-foot carrying bar away from said work-support against the force of its associated spring, means for removing the force of each of said springs from its associated bar, and manually operable means for shifting said bars away from said work-support.

30. 13. In a sewing machine, the combination of a plurality of work-engaging feet, a plurality of springs, each spring being adapted for pressing a respective one of said feet upon the work, means comprising a lever of the first order interposed between each of said springs and its associated foot for imposing upon each spring a range of movement materially longer than that of its associated foot, manually operable means to relax said springs thereby to remove the force thereof from each of said feet, and means operable upon relaxing of said springs for shifting said feet away from the work.

35. 14. The combination in a sewing machine having a frame including a work-support, a reciprocating presser-foot carrying bar, a feeding-foot carrying bar mounted for endwise reciprocating and laterally jogging work-feeding movements, a pair of springs, each spring being adapted for biasing a respective one of said bars toward said work-support, means comprising a motion-multiplying member interposed between each of said springs and its associated bar for imposing upon each spring a range of movement materially longer than that of its associated bar, inter-

mittently operable lifting means for lifting said feeding-foot carrying bar away from said work-support against the force of its associated spring, manually operable means to relax said springs thereby to remove the force thereof from each of said bars, and means operable upon relaxing of said springs for shifting said bars away from said work-support.

15. In a sewing machine, the combination of a plurality of work-engaging feet, a plurality of springs, each spring being adapted for pressing a respective one of said feet upon the work, means comprising a lever of the first order interposed between each of said springs and its associated foot for imposing upon each spring a range of movement materially longer than that of its associated foot, and manually operable means upon the movement of which the force of each of said springs is removed from each of said feet and upon the further movement of which all of said feet are shifted away from said work.

16. The combination in a sewing machine having a frame including a work-support, a reciprocating presser-foot carrying bar, a feeding-foot carrying bar mounted for endwise reciprocating and laterally jogging work-feeding movements, a pair of springs, each spring being adapted for biasing a respective one of said bars toward said work-support, means comprising a motion-multiplying member interposed between each of said springs and its associated bar for imposing upon each spring a range of movement materially longer than that of its associated bar, intermittently effective lifting means for lifting said feeding-foot carrying bar away from said work-support against the force of its associated spring, a first means to remove the force of each of said springs from its associated carrying bar preparatory to shifting the same, and means actuated by said first means for shifting each of said carrying bars away from said work-support upon the removal of said spring forces from said carrying bars.

17. In a sewing machine having a work-support, the combination of a plurality of work-engaging feet, a plurality of levers, each of said levers having its one end portion thereof in operative engagement with a respective one of said work-engaging feet, fulcrum means in engagement with an intermediate portion of each lever, a plurality of springs, each spring being in engagement with the other end portion of a respective one of said levers and being effective to bias the foot associated therewith toward said work-support, means to remove the force of said springs from said feet, and means operable upon the removal of said spring forces from said feet for shifting said feet away from said work support.

18. In a sewing machine having a work-support, the combination of a pair of work-engaging feet, a pair of levers, each of said levers having its one end portion thereof in operative engagement with a respective one of said work-engaging feet, fulcrum means in engagement with an intermediate portion of each lever, a pair of springs, each spring being in engagement with the other end portion of a respective one of said levers and being effective to bias the foot associated therewith toward said work-support, means for removing the force of each of said springs from said feet preparatory to shifting said feet, means for moving said fulcrum means out of engagement with said levers, and means for shifting said feet away from said work-support.

19. The combination in a sewing machine hav-

ing a frame including a work-support, a pair of work-engaging feet, a pair of levers, each of said levers having its one end portion thereof in operative engagement with a respective one of said feet, fulcrum means in engagement with an intermediate portion of each lever, a pair of springs, each spring being in engagement with the other end portion of a respective one of said levers and being effective to bias the foot associated therewith toward said work-support, a first means for moving said fulcrum means out of engagement with said levers preparatory to shifting said feet, and means actuated by said first means for shifting said feet away from said work-support.

15. 20. The combination in a sewing machine having a frame including a work-support, a pair of work-engaging feet, a pair of springs, each spring being adapted for pressing a respective one of said feet toward said work-support and having one end thereof secured to a single normally stationary member, means interposed in operative relative between each of said springs and its associated foot whereby each spring is given a range of movement materially longer than that of its respective associated foot, means for shifting said normally stationary member thereby to relax the force of each of said springs, and means actuated by said last mentioned means for lifting said feet away from said work-support.

30. 21. The combination in a sewing machine having a frame including a work-support, an upper feed-foot, an upper feed-bar carrying said feed-foot, a presser-foot, a presser-bar carrying said presser-foot, a pair of coil-springs, one of said coil-springs being adapted to maintain said presser-foot continuously in engagement with the work, the other of said coil-springs being adapted to press said feed-foot toward the work, intermittently effective lifting means for lifting said feeding foot off the work against the force of its associated coil-spring, a pair of relatively stiff levers, each lever having one end thereof operatively connected to a respective one of said bars and the other end thereof connected operatively to a respective one of said coil-springs, and fulcrum means in engagement with each lever so that each lever will multiply the applied force of its associated coil-spring and apply the resultant upon its associated bar.

50. 22. The combination in a sewing machine having a frame including a work-support, an upper feed-foot, an upper feed-bar carrying said feed-foot, a presser-foot, a presser-bar carrying said presser-foot, a pair of coil-springs, a single member for supporting both of said coil-springs, one of said coil-springs being adapted to maintain said presser-foot continuously in engagement with the work, the other of said coil-springs being adapted to press said feed-foot toward the work, intermittently effective lifting means for lifting said feeding-foot off the work against the force of its associated coil-spring, a pair of relatively stiff levers, each lever having one end thereof operatively connected to a respective one of said bars and the other end thereof connected operatively to a respective one of said coil-springs, a single fulcrum means in engagement with both of said levers so that each lever will multiply the applied force of its associated coil-spring and apply the resultant upon its associated bar, manually operable means connected with said single member for moving the same in a direction such as to relax said springs, and means operable upon relaxing said springs for shifting said feet away from said work-support.

23. The combination in a sewing machine having a frame including a work-support, an upper feed-foot, an upper feed-bar carrying said feed-foot, a presser-foot, a presser-bar carrying said presser-foot, a pair of coil-springs carried by said frame, one of said coil-springs being adapted to maintain said presser-foot continuously in engagement with the work, the other of said coil-springs being adapted to press said feed-foot toward the work, intermittently effective lifting means for lifting said feeding-foot off the work against the force of its associated coil-spring, a pair of relatively stiff levers, each lever having one end thereof connected operatively to a re-

spective one of said bars and the other end thereof connected operatively to a respective one of said coil-springs, fulcrum means in engagement with both of said levers so that each lever will multiply the applied force of its associated coil-spring and apply the resultant upon its associated bar, manually operable means to relax each of said coil-springs preparatory to shifting said feet, means for moving said fulcrum means out of engagement with said levers, and means for shifting said feet away from said work-support.

FREDERICK F. ZEIER.
